UNITED STATES PATENT OFFICE.

GEORGE F. LA PAUL, OF EXCELSIOR, MINNESOTA, ASSIGNOR TO CARRIE M. LA PAUL,
OF EXCELSIOR, MINNESOTA.

DEFLECTOR FOR HEADLIGHTS.

1,330,481.

Specification of Letters Patent. Patented Feb. 10, 1920.

Application filed March 6, 1919. Serial No. 230,950.

To all whom it may concern:

Be it known that I, GEORGE F. LA PAUL, a citizen of the United States, residing at Excelsior, in the county of Hennepin and State 5 of Minnesota, have invented certain new and useful Improvements in Deflectors for Headlights; and I do hereby declare the following to be a full, clear, and exact description of the invention, such as will enable others 10 skilled in the art to which it appertains to make and use the same.

My invention has for its object to provide an extremely simple and highly efficient deflector for headlights for vehicles; and, to 15 this end, it consists of the novel devices and combinations of devices hereinafter described and defined in the claims.

In the accompanying drawings, which illustrate the invention, like characters indicate like parts throughout the several 20 views.

Referring to the drawings:—

Figure 1 is a front elevation of a headlight having the deflector applied thereto, 25 with some parts shown in different positions by means of broken lines;

Fig. 2 is a view principally in vertical section taken on the line 2—2 of Fig. 1;

Fig. 3 is a front elevation of the improved 30 deflector removed from the headlight; and

Fig. 4 is a plan view of the deflector as shown in Fig. 3.

As to the parts of the headlight shown, it is important to note the casing 5, reflector 35 6 having an axially located socket 7 in which is mounted an electric light bulb 8, and lens 9 detachably secured to the casing 5, in axial alinement with said light bulb, by a clamping ring 10, which, in turn, is secured to said 40 casing by screws 11. The parts thus far mentioned are of well known standard construction.

Referring now in detail to the invention, the numeral 12 indicates the main deflector 45 which is of crescent shape and bent on an arc. The upper edge portion of the deflector 12 is also bent to form a retaining flange 13 adapted to be inserted between the lens 9 and upper portion of the clamping ring 10 50 to thereby frictionally and detachably hold said deflector in position. It will be noted that the flange 13 extends slightly more than one hundred and eighty degrees and is held against downward movement by its engage-

ment with the sides of the clamping ring 10. 55 It will also be noted that the lower edge of the deflector 12 terminates, at its central portion, above the light bulb 8.

By the use of the deflector 12, it is possible to use a clear lens, thus obtaining the maximum amount of light on the road. This deflector 12 extends downwardly over the upper portion of the lens 9 sufficiently to intercept enough of the upwardly projecting direct rays, from the light bulb 8, to prevent the same from interfering with the vision of a person in an approaching vehicle.

To prevent the upwardly projecting ray from the light bulb 8, passing under the deflector 12, from interfering with the vision of a pedestrian passing in front of the headlight, I attach to the main deflector 12 a depending supplemental deflector 14. This supplemental deflector 14 is tapered from the lower edge of the main deflector to the 75 axis of the light bulb 8 and is movably secured to the inner face of the main deflector 12 by passing a pivot 15 through one of its corners. The other upper corner of the supplemental deflector 14 loosely rests on a pin 16 secured to the main deflector 12, and supports said supplemental deflector in an operative position. For country driving, the supplemental deflector 14 is turned into an inoperative position and is supported on 80 a pin 17 also secured to said supplemental deflector, as indicated by broken lines in Fig. 1.

The main deflector 12 is preferably made of relatively thin sheet metal having a slight 90 spring. To apply the improved deflector to a headlight, the same is bent sufficiently to circumferentially contract its flange 13, and thereby permit said flange to be inserted under the clamping ring 10. In case the 95 lens 9 and clamping ring 10 cannot be sprung apart sufficiently to permit the flange 13 to be inserted therebetween, one or more of the screws 11 may be removed to release 100 said clamping ring 10 and then replaced after the deflector is in place. The removal of the deflector can be accomplished in a like manner.

From the above description, it is evident that the improved deflector may be very 105 quickly applied to a headlight or removed therefrom. It is also evident, as previously stated, that the improved deflector, while

extremely simple and inexpensive to manufacture, permits the use of a clear lens, thereby affording the maximum amount of light on the road, and, at the same time, 5 protects a person in an approaching vehicle from the strong upwardly projecting rays from the headlight. The supplemental deflector is, of course, not used during country driving, when it is not necessary to protect 10 pedestrians from the glare of headlights. It is also evident that the supplemental deflector can be very easily and quickly adjusted to and from an operative position.

What I claim is:—

15 1. The combination with a headlight for vehicles, of a main deflector for the headlight having its central lower edge portion terminating above the axis of the light bulb, and a depending supplemental deflector extending below the central lower edge portion of the deflector and tapered substantially to the axis of the light bulb, said supplemental deflector being attached to the main deflector for movement to and from an operative

position transversely of the axis of the light bulb.

2. The combination with a headlight for vehicles, of a main deflector for the headlight having its central lower edge portion terminating above the axis of the light bulb, 30 a depending supplemental deflector extending below the central lower edge portion of the deflector and tapered substantially to the axis of the light bulb, said supplemental deflector being pivotally attached to the main deflector for swinging movement to and from an operative position transversely of the axis of the light bulb, and a stop for supporting the supplemental deflector in an inoperative position above its lower edge 40 portion of the main deflector.

In testimony whereof I affix my signature in presence of two witnesses.

GEORGE F. LA PAUL.

Witnesses:

CLARA DEMAREST,
HARRY D. KILGORE.
